Stephen E. Laszlo, Brooklyn, N. Y.

Application November 24, 1954, Serial No. 33,235

Term of patent 7 years

(Cl. D52—7)

FIG. 1.

FIG. 2.

Figure 1 is a front view of a combined barometer and thermometer showing my new design; and

Figure 2 is a cross-section of the dial shown in Figure 1.

The essential features of the design reside in the dial shown in solid lines.

I claim:

The ornamental design for a combined barometer and thermometer, as shown and described.
